UNITED STATES PATENT OFFICE.

EDWARD W. WHEELER, OF CHICAGO, ILLINOIS.

DRESS-LINING.

SPECIFICATION forming part of Letters Patent No. 272,813, dated February 20, 1883.

Application filed November 20, 1882. (No model.)

To all whom it may concern:

Be it known that I, EDWARD W. WHEELER, of Chicago, in the county of Cook and State of Illinois, have invented certain new and useful improvements in Linings for Ladies' Dresses; and I do hereby declare that the following is a full, clear, and exact description thereof, reference being had to the accompanying drawings, and to the letters of reference marked thereon, which form a part of this specification.

This invention relates to linings for ladies' dresses and other garments, and has for its object to provide a construction in these articles by which they may be manufactured and sold in quantities of assorted sizes to dry-goods dealers and others, with a view to their being selected and purchased by the purchasers of dress-goods, and of serving in their hands as suitable guides in cutting the dress to fit the person.

To this end the invention consists in a dress-lining having all its body seams and darts ready basted, and provided with an exceptionally wide hem, or, preferably, with unfolded material for such hem, at the front margins of the garment, in order to enable the same to be varied to suit the several circumferential measurements of the person.

It also consists in a series of dress-linings as articles of manufacture, made of alternate sizes, and provided severally with material for exceptionally wide hems at the front margins of the garment, in order to provide for the intermediate sizes, or, in other words, to provide for the adaptation of such sizes as are furnished to fit intermediate sizes, all as will be fully explained.

In the drawings, Figure 1 illustrates a waist-lining in form as if applied to the person, and Fig. 2 is a front view of the same thrown apart in front to better illustrate the variation in width of the front hems contemplated by my invention for the purpose of adapting the lining to different figures.

A is the body of a waist-lining, having its side and other seams and its darts suitably located and basted, and having at the front margins, B B, an extra allowance of material adapted to be folded to form hems, whereby necessary variations from the regular bust, neck, and waist measures may be provided for by a variation in the depth of the fold along these

margins of the garment. Thus, to illustrate, a a may represent lines marked on the goods at which the fold will be made in a symmetrical figure of the smallest size to which the lining will be ordinarily applicable. b b, then, may represent such actual lines of fold as may be made in the front hems to fit the garment to somewhat irregular variations from a symmetrical form—that is to say, the make-up lining is selected with reference to a fit at all points excepting the front bust-measure and the circumferential measurements of the waist and neck. The front margins, B B, are then drawn together and pinned along a line equally distant from both edges, such as will insure a properly close fit of the lining to the person, and the fold of the hems is made in the line of the pins, or in a line parallel and a sufficient distance outside the pins to permit the margins to overlap after the hems are completed.

By long experience and observation as a fitter of ladies' dresses I have found that linings for a certain general size and class of figures may usually be adapted to all persons of the same general size and class by simply varying the front bust-measure. Sometimes, however, slight variations may be additionally required for the waist and neck. It is therefore practicable to furnish linings fitted to all persons by providing in each lining sufficient material at the front margins to allow a suitable change for the larger busts. When the figure is entirely symmetrical, the hem will thus be made wider, and when the front bust-size is greater the hem will be narrower. The less variation for waist and neck will also be provided for in the material supplied for the more frequently and more widely varying bust-size. It is thus made possible to supply linings ready made and to be kept in stock for all sizes and classes of figures, from which all persons of normal figure may select a perfect fit, all that is required being to pin the front margins, B B, so as to make the front smooth on the person and to fold the hems to correspond. This is entirely practicable and easy, even for the most unskilled person, without assistance, for the reason that the front margins of the lining are both visible and accessible for manipulation by the wearer to whom the lining is to be adjusted.

It is contemplated to furnish to the trade

linings ready basted and in series of alternating sizes—as, for example, Nos. 32, 34, 36, &c., (bust-measure)—and to provide such additional amplitude of material on the front margins, 5 or at B, as will suffice to adapt the same lining to fit the next size larger—as, for example, a No. 32 will fit No. 33 bust, and so of other measurements. By means of the surplus material provided in the front margins a perfect fit may 10 be readily obtained for any normal figure by merely folding the margins as may be required to suit the figure, and all figures may be fitted by furnishing only one-half as many linings or 15 garments as there are sizes and classes of figures to be provided for.

I am aware that dress-linings have been manufactured in halves—as, for example, a front and back part separate, and requiring to be joined in the shoulder and side seams. This 20 construction makes the aid of a second person necessary in fitting, while in the construction as above set forth the wearer is entirely able to produce the fit without assistance, since the adjustment of the front part of the lining may 25 be accomplished solely by a movement of the arms and without distortion of the part of the body to which the lining is being fitted.

Of course it is entirely allowable and practicable, in accurately fitting the lining described 30 to exceptional figures, to open and vary any of the seams as may be necessary and as here-

tofore commonly practiced by dress-makers; and a sufficient quantity of material may 35 ad- visably be left at these seams or at either of them (as at the center back) for this purpose. 40 This is not essential to my invention, however, which contemplates provision at the front of the garment for the more common variations in the size of the figure found to exist at this point.

I claim as my invention—

1. As an article of manufacture, a ready-made 45 waist-lining having its seams and darts basted, and having an excessive amount of material in its front margins, whereby the garment is adapted to be folded to form the front hems in such lines as may be necessary to produce a required fit.

2. As an article of manufacture, a series of 50 dress-linings of alternate sizes, each lining provided with an excessive amount of material at its front margins, whereby each lining is adapted to be fitted to a figure requiring the next larger size, substantially as set forth.

In testimony that I claim the foregoing as 55 my invention I affix my signature in presence of two witnesses.

EDWARD W. WHEELER.
